UNITED STATES PATENT OFFICE.

JOHN LIVINGSTONE, OF MONTREAL, QUEBEC, CANADA,

FIRE-BOX FOR STEAM-BOILER FURNACES.

No. 853,099.

Specification of Letters Patent.

Patented May 7, 1907.

Application filed July 21, 1906. Serial No. 327,157.

To all whom it may concern:

Be it known that I, JOHN LIVINGSTONE, a subject of the King of England, residing at Montreal, Quebec, Canada, have invented a new and useful Improvement in Fire-Boxes for Steam-Boiler Furnaces, of which the following is a specification.

My invention is in the nature of certain improvements in the fire-boxes of steam boiler furnaces and especially the furnaces of locomotive boilers.

It is designed to accomplish several important results, prominent among which are. First, to contribute to the strength and stability of the boiler around the fire-box by maintaining, while in service, the natural elasticity of the material, avoiding the burning of the inner ends of the stay-bolts and avoiding those strains which ordinarily exist between the stay-bolts and the outer and inner walls of the fire box due to high temperatures of unequal distribution. Secondly, to secure a more perfect combustion of, usually, unconsumed carbon, and thus economize fuel and avoid the nuisance of smoke. Thirdly, to assure a continuous production of free hydrogen in the fire-box and fourthly, to give relief from explosion.

The instrumentalities invented by me for securing the results under the first heading are precisely the same as those which accomplish the results under the second, third and fourth headings and these instrumentalities consist in a very simple and practical application of hollow stay-bolts which, while not new in themselves, involve, when constructed and applied in accordance with my invention, the most important results in steam boiler furnaces.

Figure 1 is a vertical longitudinal section through the fire-box of a locomotive boiler. Fig. 2 is a vertical transverse section through the same, on line 2—2 of Fig. 1. Fig. 3 is an enlarged central section of one of the crown stay-bolts and Fig. 4 is a similar view of one of the horizontal stay-bolts as used at the sides, back and front of the fire-box.

In the drawing, A represents the outer wall and B the inner wall of that portion of a locomotive boiler which surrounds the fire-box C.

D are stay-bolts which connect the crown sheet of the furnace to the top portion of the outer wall and E are stay-bolts which connect the outer and inner walls at the sides, back and front ends of the fire-box.

The stay-bolts as shown are all screw threaded their entire length, but they may be threaded only at the ends where they pass through the outer and inner walls of the boiler. I prefer the Whitworth standard to the V-threads. Their outer ends are firmly riveted or upset to form heads or they may be made fixtures in any other suitable way.

The horizontal stay-bolts E, see Fig. 4, have a central longitudinal hole e through them from end to end and embody no constructive novelty. The stay-bolts D, of the crown sheet are, however, specially constructed, as seen in Fig. 3. They have a central longitudinal hole d, which does not go all the way through, but stops short of the outer end of the stay-bolt, so that it does not communicate with the outer air. It does go all the way through the inner end of the bolt, however, and it communicates with a number of small holes d' d' drilled transversely into the stay-bolt and opening on the outer side into the steam space in the boiler between its two walls, so that steam from the steam space may gain access to the central hole in the stay-bolt and flow in a small stream into the fire box. The steam expands in the central hole; it there meets and absorbs the heat radiating from the fire, but as it gives back the heat as freely as it absorbs it, the radiation, conduction, and diffusion of the heat is quickened to the outer wall; the side sheets, back head and front end receiving the radiant heat of the fire at the same time as the crown sheet, and all at the same time with the radiant heat up d and by conduction up D and by diffusion through the water, and with the heat at the outer wall confined by the lagging, an equilibration of the temperature between the two walls is attained.

The service of the steam in the central hole d is also of value to the material; in that, whereas in solid stay-bolts the material becomes fatigued and weakened in service, it saves and sustains the material in its elastic strength, provided the iron is free from the impurities which cause crystallization and brittleness. The central hole d is also a safety hole in case of breakage for though the natural supply of steam from openings d' is invisible, the breakage of a bolt would cause a visible escape of steam to give notice of such breakage of a bolt or bolts, and the same remarks apply to the opening e in stay-bolts E. As this stream of steam passes

through the highly heated end of these stay-bolts, the issuing steam is invisible, and superheated to the point of disruption into its constituent gases, oxygen and hydrogen. Just 5 at this point two important and simultaneous results may be noted. The first is the cooling of the end of the stay-bolt in the inner wall by the escaping steam and increasing, the strength, stability, and longevity of 10 the stay-bolt by taking away its damaging excess of heat, and the second is in utilizing this heat by giving it to the steam for superheating the same and rendering it susceptible to disruption with the consequent formation 15 of water gas by the association of its gases with the incandescent particles of the fuel.

The streams of superheated steam form, 20 when disrupted, fuel gases which mingle with the oxygen of the air passing through the lower stay-bolts, and produce an intense combustion which burns up the smoke and carbon particles.

In the ordinary way of burning the fuel, 25 there are three forms of loss from out of the combustibles; irrespective of losses by burning coal weighted with constituent incombustibles. The three forms of loss, are; first, the loss of the volatile constituents of bituminous 30 coal. Second, the loss by the formation of the always forming carbonic oxid. Third, the loss by the escape, unconsumed, of the carbon particles from the furnace, in part lodging in the front end, where they accumulate 35 and impair the draft, and in part as sparks through the smoke stack, sometimes causing fires.

Professor Goss, the scientist of Purdue University, has determined, by test, that the 40 weight of sparks and cinders, which escape as above, unconsumed, to the front end and outer air, may in connection with narrow fire boxes equal 20 per cent. of the fuel fired. The three forms of loss even with careful firing 45 in the fire boxes generally in service, may aggregate 50 per cent. of the weight of the combustibles in the coal fired.

All devices have been conceived and invented to coerce the air or restrain the gases, 50 and the smoking chimneys, stacks, and funnels prove the principles of their conception to be unscientific.

I have determined by test that the carbon particles which ordinarily escape to the front 55 end as cinders and out of the smoke stack as sparks, can be burned in the fire-box, by the production of free hydrogen from the steam at its point of exit from the tubular channels *d* and in the passage of the superheated steam over the incandescent coal.

The affinity of hydrogen (1) for oxygen, 60 and the oxygen always present when wanted in never cooling volumes by way of the tubular channels *e* maintains the temperature above the temperature at which carbon ig-

nites, and (2) the affinity of hydrogen for carbon, makes it the gas to overtake and burn in the fire-box the carbon particles which would otherwise escape to the front end as cinders and to the smoke stack as 70 sparks. When the volatile portion of the bituminous coal is spread over the red fuel, it rises above the fire bed and quick as a flash it is in the air as smoke; and when the solid coal under the influence of the incandescent 75 fire bed gives off unburned, partly burned, or coked portions called carbon particles, they rise in the furnace and pass through the tubes to the front end or out of the stack, and there is no other gas but hydrogen to overtake and 80 consume the carbon particles while they are in the fire-box, because there is no other gas equal to it in diffusive and refractive power; it diffuses relatively at the rate of four to one for oxygen, the velocity of its atoms is 6,050 85 feet a second with oxygen 1,514, and nitrogen, (which aids the draft) 1,616 feet a second, all combining with the first stage of burning on the grate and perfected by the production of hydrogen at *d* and by the union 90 of the carbonic oxid with the oxygen from *e*. Most efforts to superheat and disrupt steam in a fire-box involve a destruction of the material forming the instrumentalities, but in my invention, it will be seen, that the gassifying of the steam is made to cure an existing 95 evil, namely, the burning of the inner ends of the stay-bolts, so that I secure two advantageous results without the hitherto attendant objections of either, or in other words 100 while securing a great desideratum in stimulating combustion, I by the same instrumentalities and at the same time, without other expense, dispose of a very serious evil, by the preventing of the burning of the inner 105 ends of the stay-bolts and the avoidance of differential temperature strains at the anchorage points of the stay-bolts in the walls of the boiler.

It is well known that the railway companies are greatly embarrassed by the breakage of stay-bolts. The alleged cause of the abnormal breakage is in the greater temperature and expansion of the inner sheet, (next to the fire) acting on the bolts taut in the outer sheet of the fire-box where the temperature is less. That cause produces differential expansion and contraction in the stay-bolts in the varying temperatures of the fire-box, which sooner or later, causes crystallization 115 and breakage. The danger increases with every bolt broken, sometimes causing explosions and loss of life with appalling suddenness. When from any cause, the conduction through the material is impaired, and any part of the iron within the boiler becomes red hot, then water or steam released by a breaking stay-bolt will, in touching the red hot iron, cause a sudden explosion.

I have determined by tests that the gases 120

released by disruption may be continuously produced without an explosion, and that there is a relief from explosion when there is an exit to the air. The gases released in disruption expand into space whether the space be a vacuum or filled with another gas, and as there is no outlet so small that the gases will not as instantaneously with the explosion find and pass through, there is a relief from explosions in the small holes d' d'' and in the center hole d , the expansion losing its energy by its dissipation through the fire-box, tubes, and smoke stack in the outer air.

Other dangers arise from burning: When stay-bolt ends burn, the burning may follow the line of the fibers up the bolt until cooled by the water, and the cooling may not occur until half the bolt is destroyed, especially if it is coated all round with non-conducting impurities from the water. In such burning heat, the iron loses its cohesion and hardness, becomes lessened in tenacity, and sometimes its molecular form may be altered to a crystalline structure, and the sheets in expanding are antagonized by the expanding bolts and crack.

By reason of direct exposure to high heat the ends of stay-bolts exposed to the fire, are quickly destroyed since they have no protection by touch with the air, envelopment in steam, or by conduction of their heat at the junction of the bolt and the sheet; their connection there being only a mechanical connection by screwing into the sheet and riveting thereon. The tenacity of the iron therefore becomes less, sometimes so much so that it fails to endure the steam pressure, which forces the sheet out from the threads and pulls the head through the sheet.

The railway companies are also continuous losers and the people injured by reason of the excessive waste of fuel, in smoke escaping through the smoke stack, and partly burned coal, escaping as sparks, causing damages and suits for damages, also by reason of the loss and waste of cinders, lost to the fire, by escaping through the tubes to the front end of the locomotive and thus interfering with the draft. There is also much interference in making steam, by reason of coatings of soot in the tubes, the soot being a non-conductor, preventing the conduction of the heat through the tubes.

Coatings of soot in the tubes come from imperfect combustion, but given the conditions which burn the carbon to carbon dioxide, and a good natural draft to lead the carbon dioxide through the tubes to the stack, in its passage it will dissolve the soot in the tubes and in the tubes so swept clean, there will be perfect conduction.

The outlay by railways for weekly or monthly tests with a hammer to discover by sound the broken stay-bolts is an uncertain and costly way by which to discover break-

ages, and while adding more to that cost, the drilling of tell tale holes in the ends, is of disputed good, in fact an evil, whereas in my invention there is a warner at the exit end of every stay-bolt in the fire-box to report 70 breakages when breakages occur, without the touch of a hammer or the cost of a cent.

My invention in meeting the various objections noted serves 1. To effect an equilibrium in the temperature between the inner 75 and outer sheets of the fire-box. 2. To increase the steam service from the heating surface without enlargement of the boiler. 3. To quicken the service of heat to the outer sheet at even time with its service to the inner sheet by radiation and the uniform diffusion of the heat in the water by conduction. 4. To cause the combustibles now wasted as smoke, the cinders now lost in the front end, (there impairing the draft) and the sparks 85 now sent out of the smoke stack, to be burned in the fire-box. 5. To protect the ends of stay-bolts from burning and lessen the expansion of the bolts with relief from cracking, in the expanding sheets. 6. To 90 convert continuously, when in service, the solid fuel into combustible gases. 7. To furnish oxygen to burn the combustible gases formed in the process of burning. 8. To dissolve the soot, as it settles in the tubes. 9. 95 To promote a draft to aid in the passage of the always forming carbonic acid through the tubes to the smoke stack. 10. To produce and burn hydrogen in the fire-box, to maintain the temperature and therewith 100 oxygen consume the gases, cinders, sparks, and smoke, by taking them into union. 11. To give general relief in conditions which cause explosions.

I claim

1. A steam boiler furnace having the outer and inner walls of the fire box connected by hollow stay bolts having solid outer ends and opening into the furnace at their inner ends and having one or more lateral openings establishing communication between the interior of the boiler and the hollow stay bolt.

2. A steam boiler furnace having crown sheet stay bolts formed with solid outer ends and steam spaces opening into the fire box.

3. A steam boiler furnace having crown sheet stay bolts formed with solid outer ends and steam spaces opening into the fire box and horizontal stay bolts connecting the two walls of the lower part of the fire box and having air channels extending entirely through the same.

4. A hollow stay bolt for a steam boiler having one end made solid and closed, the other end open and one or more lateral inlets 125 to the interior between the ends.

JOHN LIVINGSTONE.
